UNITED STATES PATENT OFFICE.

LUDWIG SILLAND, OF EDWARDSVILLE, ILLINOIS.

HARROW.

SPECIFICATION forming part of Letters Patent No. 248,221, dated October 11, 1881.

Application filed August 17, 1881. (No model.)

To all whom it may concern:

Be it known that I, LUDWIG SILLAND, of Edwardsville, in the county of Madison and State of Illinois, have invented a new and useful Improvement in Harrows; and I do hereby declare that the following is a full, clear, and exact description of the same, reference being had to the accompanying drawing, forming part of this specification, in which the figure represents a top view, partly in section, of my improved harrow.

My invention relates to improvements in harrows; and it consists in the peculiar construction and arrangement of the draft-rods and connecting-links, whereby the draft can be applied to two or more sections of the harrow, as desired.

The harrow proper consists of several interchangeable duplicate sections or members, A, of which any desired number may be employed at a time. Each section A is composed of four parallel beams, B B' B² B, each carrying four or more teeth, b. The beams are secured together and held in place by parallel tie-bolts C, passing transversely through the beams and through distance-blocks D.

It will be seen in the accompanying drawing that the outer parallel beams B of each section A of the harrow are of about the same length, and that the beam B' projects out beyond the beams B on the right side of each harrow-section A, and that the beam B' does not project as far as the beams B on the left side of each harrow-section. The transverse beam B² of each section is arranged in the reverse manner to the beam B', so that the beam B² projects beyond the beams B on the left side of each harrow-section, its oppositeright-hand end not projecting out as far as the beams B. By this construction it will be seen that each section (when the harrow-sections are connected together, so that the ends of the transverse beams B B' B² abut against each other in the several sections) will, in the forward movement of the connected sections, harrow a portion of the soil over which its adjacent section also passes. By this arrangement of the beams, also, the teeth can be so arranged therein that not one of them will follow in the track of another.

To the rear ends of each section A are secured

two short chains, G, one of which is provided with a hook, a, so that when harrowing rough ground the sections can be connected together at their rear ends.

H is a strip of wood secured to the upper faces of the beams of each section and projecting rearwardly, and provided with a handle, h³, by means of which the section may be raised from the ground to allow it to be freed of weeds, &c., that may have gathered in the teeth.

The teeth in the ends of each section of the harrow are secured in place by means of nuts c, whereby they may be readily removed when harrowing corn-ground or other plants in rows, and thus not destroy the corn or other plants.

The sections A of the harrow are connected at their front ends to the draft-beam E by means of parallel pull-rods F, secured to the beams B B' of each section. The pull-rods F are provided at their forward ends with eyes connected by clevises with the draft-beam E. The draft-beam E is made in two sections, S S', which are coupled together by means of parallel plates e, arranged on opposite sides of the draft-beam at the junction of the sections. The plates e are secured together and to the sections of the draft-beam by bolts passing through the plates and sections of the draft-beam, and provided with nuts. By this construction the sections of the draft-beam are securely coupled together, and can readily be uncoupled when desired.

h represents an eyebolt secured to the draft-beam E at or near its middle when the draft-beam is composed of two sections coupled together, as described.

h' h' represent eyebolts secured to the draft-beam E near the ends of its sections.

k represents a link provided with an eye at each end, one of which engages with the eyebolt h' at one end of the draft-beam and the other with a ring, l.

m represents a hook with an eye at its outer end, which engages with the ring l, the hook engaging with the eye of the eyebolt h.

o represents a hook having an eye at one end, which engages with the ring l, the opposite end of the hook engaging with the ring p.

q represents a link with an eye at each end, one of which engages with the eye of the eye-

bolt h' at the opposite end of the draft-beam, and the other eye engages with the ring p .

r represents a link with an eye at each end, one of which eyes engages with the ring p and the other engages with the eye of the central eyebolt, h , secured to the draft-beam.

From this construction it will be seen that if it is desired to use three sections of the harrow the draft is applied to the ring l , the parts being arranged as above described. If it is desired to use but two sections of the harrow, the plates e are removed, uncoupling the sections of the draft-beam, and the hooks $m\ o$ are removed from engagement with the eyebolt h and ring p , when one section of the harrow will

become disengaged from the other two, and the draft-power to operate the two sections is applied to the ring p .

I claim as my invention—

The combination, with the section S of the draft-beam, provided with the eyebolts $h\ h'$, links $q\ r$, and ring p , of the removable section S' of the draft-beam, link k , ring l , and hooks $m\ o$, substantially as described, and for the purpose set forth.

LUDWIG SILLAND.
